(57) **CLAIM**

The ornamental design for a stackable goalie stick paddle height extender as shown and described.

DESCRIPTION

FIG. 1 is a right side view of a stackable goalie stick paddle height extender showing my new design.

FIG. 2 is an exploded front view thereof, in a stacked configuration.

FIG. 3 is a top, front and right perspective view thereof, in a stacked configuration.

FIG. 4 is an exploded top, front and right perspective view thereof, in a stacked configuration and in a state of use; and,

FIG. 5 is a top, front and right perspective view thereof, in a stacked configuration and in a state of use.

The broken lines in the drawings depict environmental

subject matter and form no part of the claimed design.
